UNITED STATES PATENT OFFICE

NATHAN MICHELMAN, OF BROOKLYN, NEW YORK

METAL DOOR

Application filed December 24, 1927. Serial No. 242,414.

This invention relates essentially to a metal door or similar article having a front and back which is constructed of two sections of steel or similar analogous metal plate 5 shaped to simulate each other, and it comprehends devices for locking the two sections together in spaced relation to each other.

An object of the invention is to shape each section by forming the stiles, rails, molding 10 and panel integral thereby producing the front or back unit with its sunken panels merely by shrinking and applying pressure to a steel plate.

Another object of the invention is to securely fasten the front and back walls together after the units are completely shaped, by means of a metal key arranged to extend 15 from the top to the bottom in the space adjacent the sides of the two units.

Another object of the invention is to provide a key keeper welded to the inner side 20 portion of each section before the sections are positioned together, so that in order to interlock the sections rigidly together it will only be necessary to drive the key into a groove formed by the keeper members.

Another object of the invention is to provide reenforcing devices welded to each wall 25 of a unit and associated with a metal bar whereby the front and rear panels which are surrounded by a contiguous molding are prevented from buckling.

The invention resides more particularly in the novel combinations hereinafter described 30 and claimed, reference being made to the accompanying drawings in which:

Fig. 1 represents a front elevation of a door embodying this invention.

Fig. 2 is a side or edge view of the same.

Fig. 3 is a vertical longitudinal section taken along the line 3-3 of Fig. 2.

Fig. 4 is a horizontal transverse section taken along the line 4-4 of Fig. 1 on a larger scale.

Fig. 5 is a perspective view of a keeper unit.

In the drawings the numeral 6 designates a panel, 7 is the molding, 8 is the stiles and 9 is the rails of a door unit formed from a single sheet of steel and stamped to the shape shown. Each side 10 is integral with the

stiles and is bent at right angles to the front and rear walls. The other unit is a counterpart of the unit noted above and is adapted to be placed onto the first unit with the edges of the side walls in contact and the surfaces 55 flush with each other.

The means for locking the two units together consists of keeper members as indicated in Fig. 5, each having a wall 11 whereby the member is spot welded to the inner surface adjacent the stile of a unit. One wall 11 is thus fastened to one of the units and the wall of the other keeper is secured in a similar way to the second unit. When the two units are positioned together the two keeper members 60 are brought into register or alignment by tongues 12 engaging openings or slots 13 located in the edge of the guide keepers and alternating with the tongues. The inner edge of the slot impinges on a shoulder 14 65 so as to limit the lateral movement of one member relative to the other. The tongue of each member is bent inwardly as shown at 15 so as to form a substantially rectangular groove extending from the top to the bottom 70 of the unit.

A metal key 16 is forced into the groove and through holes respectively located in the top and bottom of channel plates 17 while the ends thereof can be brazed to the front 80 and back plates thereby preventing displacement. There are two of the keys shown in Figs. 3 and 4 one for each side and they effectively in conjunction with the keepers form invisible fasteners to hold the two door 85 units together. The channeled plates 17 permit the upper or lower edge of the rail to be filed or ground without fracturing the surface of the metal when the door is installed and they form a reenforcement for the walls. 90 The two door units when joined together form the front and back of the door with a space therebetween in which can be packed a sheet 18 of non-heat conducting material such as asbestos.

A device for obviating warping or buckling of the panels of each unit includes, a metal bar 19 inserted in a hole centrally located in the top and bottom channeled plates. The bar coacts with metal strap members each 100

having a support or base 20 whereby the member is spot welded to its respective panel. When in place the bar extends from the top to the bottom of the channel so as to stiffen the panels.

5 I claim:—

1. A metal door comprising front and back wall sections each section shaped with integral stiles and rails from a single sheet of steel, each section having a pair of integral side members which abut against the edges of the adjacent side members to create an air space between the walls of the sections with a packing material arranged therebetween, a top and bottom channel plate secured to the sections and a plurality of holes located in the plates, pairs of interlocking keepers welded to the inner portion of the sections adjacent the abutting edges, and a key passing through each hole made to engage the keepers so as to lock the sections together.
2. A metal door comprising front and back wall sections each section shaped with integral stiles, rails and panels from a single sheet of steel, each section having a pair of integral side members which abut against the edges of the adjacent side members to create an air space between the walls of the sections with a packing material arranged therebetween, a top and bottom channel plate welded to the sections and a plurality of holes located in the plates, pairs of interlocking keepers welded to the inner portions of the sections adjacent the abutting edges, a key passing through each hole made to engage the keepers so as to lock the sections together, straps welded to each of the sections behind the panel, and a bar inserted in one of the holes in the upper channel member and passing through a hole in the lower channel member made to engage the straps.

In testimony whereof I have hereunto set my hand.

NATHAN MICHELMAN.
